ABSTRACT: Torpedo-steering control and roll-stabilization apparatus comprising four bodily movable steering fins mounted in quadrature relationship around the tail cone with their fin shaft ends extending through the shell wall, and a unitary-actuator assembly for actuating the ends of the fin shafts. The frame of the actuator assembly is an annular ring adapted for transverse mounting across the interior of the shell ahead of the fins. The ring has a substantially square opening with the sides of the opening perpendicular to the fin shaft axes. Three upstanding lugs are affixed to the front face of the ring adjacent three of the sides of the opening. The upstanding lugs carry three identical fin actuators including a servomotor driven worm meshed with a worm wheel. The worm wheel has an aperture along its axis adapted to engage the inner ends of the fin shafts along its axis. The actuators are fastened to the lugs by adjustable means permitting alignment of the worm wheel aperture with the fin shaft prior to the actuator being secured in place. The bodily movable fins have integral fin shafts, with the fin shaft axis passing through the fin slightly ahead of the hydrodynamic center of pressure of the fin. Two diametrically opposite fins are driven independently by different actuators producing a combination joint deflection steering command and a differential deflection steering command to yield steering command and a differential deflection steering command to yield steering control in one steering plane, and yield roll control. The other steering fins are coupled by a yoke and driven by a deflection steering command yielding steering control in the other steering plane.

TORPEDO-STEERING CONTROL AND ROLL-STABILIZATION APPARATUS

The invention described herein may be manufactured and used by or for the Government of the United States of America for governmental purposes without the payment of any royalties thereon or therefor.

The invention relates to torpedo steering surface apparatus of the type in which four quadrature-spaced deflection surfaces are operated to provide triaxial control, i.e. control in two steering planes and roll control.

From the earliest times, torpedoes have required fixed stabilization fins to provide roll stability. The principle of providing roll control by means of a differential deflection command between a pair of diametrically opposite steering surfaces has been used to increase roll stability. This has been disclosed in U.S. Pat. No. 2,974,260 to F. S. Malick et al., entitled "Triaxial Control System." However, the apparatus of that patent operated small steering tabs only, and fixed stabilizing fin structure was nevertheless still required to achieve roll stability.

An object of the present invention is to provide steering apparatus which achieves triaxial control without the need of any fixed stabilization surface, whatsoever.

Another objective is to provide apparatus in accordance with the preceding objective which can be made by standard manufacturing methods, and which nevertheless meets the severe environmental and performance requirements of modern air-dropped, high-speed, antisubmarine torpedoes.

Other objects and many of the attendant advantages of this invention will be readily appreciated as the same becomes better understood by reference to the following detailed description when considered in connection with the accompanying drawings wherein:

FIG. 1 is a central longitudinal section of the tail cone zone of a torpedo, portions being shown in side elevation;

FIG. 2 is a view of the unitary actuator assembly taken along arrow 2, FIG. 1, the torpedo shell, motor and drive shaft being omitted for clarity;

FIG. 3 is a view taken at line 3-3, FIG. 2;

FIG. 4 is an enlarged view of a detail taken at the line 4-4, FIG. 3;

FIG. 5 is a detailed enlarged longitudinal section of the end portion of a fin shaft in FIG. 3; and

FIG. 6 is a section taken along lines 6-6, FIG. 2.

Referring now to FIG. 1 of the drawing, there is shown a tail portion of an antisubmarine homing torpedo 10 whereat the propulsion system elements and steering apparatus are located. A tail cone 12 is concentrically aligned about the torpedo axis A, and has a removable propeller shaft block 14 threaded in place at its rear end. A pair of yaw steering fins 16U and 16L and a pair of pitch steering fins 16S and 16P are rotatably mounted to the shell by means of shaft bearings 18 associated with inwardly projecting bosses 22 formed on the inner surface of the shell. The yaw steering fins 16U, 16L are aligned about a vertical axis B and the pitch steering fins 16S, 16P about a horizontal axis C, FIG. 2. The fins all have integral shafts 20 so that the entire fin bodily moves under rotation of its shaft. Each fin shaft axis is located slightly ahead of the center of pressure (indicated on the drawing as C. P.) of the fin surface. A propulsion motor and associated output gearing is contained in a centrally mounted housing 26 having a bell-shaped rear end. A pair of axially aligned concentric contrarotating drive shafts 28a, 28b, drive a contrarotating propeller system comprising hub and propeller assemblies 30a, 30b. A unitary actuator assembly 32 for driving all three fins comprises a ring 34 attached by anchor boats to planar surfaces on the front sides of bosses 22, and three identical individual actuators 36U, 36L and 36S, for driving fins 16U, 16L and 16S respectively. The shaft of fin 16P is connected to the shaft of fin 16S by a clamping block attached to yoke assembly 38, FIG. 2, having a central aperture through which drive shaft 28 may extend. A U-shaped bracket 40 for holding a multiconnection electric plug 42 is affixed to ring 34. For purposes of simplicity, much of the wiring between com-

ponents of the actuator and multiconnection plug 42 is omitted.

Referring now to FIGS. 2 and 3, ring 34 has a substantially square opening 43 with its sides perpendicular to the steering fin axes B and C. forwardly projecting upstanding lugs 44U, 44L and 44S are affixed to the front face of ring 34 adjacent to the sides of opening 43 nearest fins 16U, 16L and 16S, respectively. Each lug is laterally offset from the fin axis by a distance D, the offset always being to the right-hand side of the axis as the lugs appear in FIG. 2. A threaded aperture 46 is provided in each lug.

Since the actuator assemblies are all alike the following description of arrangements of components thereof will serve for all.

15 A flat gearbox 48 contains a worm 50 meshed with a segmental worm wheel 52. The segmental worm wheel is pivotally held in the box in perpendicular relationship to the opposite face plates 54a and 54b of the gearbox. The worm 48 is journaled between sides of the gearbox in alignment along worm axis E. A gearbox lug 56 is formed as an extension of the faceplate 54b of the gearbox. An elongated slot 58 is formed in the gearbox lug having its major axis F parallel to worm axis E. Each individual actuator 36 is fastened to ring 34 by a bolt 60 which extends outwardly through a slot 58 and engages the

25 threaded aperture 46 of the adjacent upstanding lug 44 of the ring. Bolt 60 holds the outer surface of lug 56 in engagement with inner surface of lug 44, which in turn aligns the gearbox in perpendicular relationship to its associated fin axis. A reversible servomotor 62 is coupled to worm 50 through a shaft extension 64 enclosed by a cylindrical housing 66. Servomotor 62 is a high-performance direct-current permanent-magnet-type motor having a response time of less than 15 milliseconds. (Response time is defined as the time it takes the motor to accelerate to approximately 63 percent of its terminal speed.) The requirements for steering a modern high-speed antisubmarine homing torpedo typically require 10 servomotor reversals per second, so that fast responses are needed. High performance servomotors may be obtained commercially, as for example, from Globe Industries of

30 Dayton, Ohio. The diametrically opposite protuberances 68 (best shown in FIG. 2) of the servomotor housing contain the permanent-magnet structures. The protuberances 68 are disposed in a chordal relationship to the interior of shell 12, as best shown in FIG. 2. The opposite end 70 of the worm shaft

35 projects from the gearbox in order to provide a connection for a conventional-shaft-position followup potentiometer, which has been omitted from the drawings for purposes of simplicity. Segmental worm wheel 52 is journaled between the inner and outer wallplates 54a, 54b and connected to the ends of the fin shafts 20 as follows. A round bearing shoulder 72 is concentrically formed about the axis G of the worm wheel on each of the opposite faces. A square aperture 74 extends through the worm wheel and the bearing shoulders along axis G. The square aperture is for receiving a square shank 75 formed on the end of each fin shaft 20 for purposes of engaging the worm wheel. This square shank is shown in the cutaway of the gearbox of individual fin actuator 36L. The bearing shoulders 72 are mounted to the walls 54a, 54b by means of a ball bearing 76 held in an eccentric bearing retainer ring 78. As best shown in FIG. 4, the inner periphery 80 of bearing retainer ring is eccentric (exaggerated in drawing) relative to its outer periphery, so that the axis G of the worm gear is held in eccentric relationship to the outer periphery of retainer ring 78. The retainer ring 78 is fastened to the gearbox wall by three screws 82 extending through a flange formed on the retainer ring. A set 86 of three incrementally spaced holes are provided for each screw 82, so that the eccentric retaining ring can be fastened in any of three incremental angular positions depending upon which hole of the sets is used. This arrangement provides adjustability of the mesh between the worm and worm wheel to compensate cumulative effects of manufacturing tolerances in minimizing backlash. This adjustment is made at the time of assembly of the gearbox. In an operational unit like the embodiment on the drawing,

40 45 50 55 60 65 70 75 80 85 90

Segmental worm wheel 52 is journaled between the inner and outer wallplates 54a, 54b and connected to the ends of the fin shafts 20 as follows. A round bearing shoulder 72 is concentrically formed about the axis G of the worm wheel on each of the opposite faces. A square aperture 74 extends through the worm wheel and the bearing shoulders along axis G. The square aperture is for receiving a square shank 75 formed on the end of each fin shaft 20 for purposes of engaging the worm wheel. This square shank is shown in the cutaway of the gearbox of individual fin actuator 36L. The bearing shoulders 72 are mounted to the walls 54a, 54b by means of a ball bearing 76 held in an eccentric bearing retainer ring 78. As best shown in FIG. 4, the inner periphery 80 of bearing retainer ring is eccentric (exaggerated in drawing) relative to its outer periphery, so that the axis G of the worm gear is held in eccentric relationship to the outer periphery of retainer ring 78. The retainer ring 78 is fastened to the gearbox wall by three screws 82 extending through a flange formed on the retainer ring. A set 86 of three incrementally spaced holes are provided for each screw 82, so that the eccentric retaining ring can be fastened in any of three incremental angular positions depending upon which hole of the sets is used. This arrangement provides adjustability of the mesh between the worm and worm wheel to compensate cumulative effects of manufacturing tolerances in minimizing backlash. This adjustment is made at the time of assembly of the gearbox. In an operational unit like the embodiment on the drawing,

backlash is maintained to values which enable coupling of the mechanical motion from servomotor 62 to the fins without any appreciable degradation of its 15 millisecond response characteristics.

Each gearbox 48 is attached to the lug 44 with the angle between the worm axis E and the torpedo central plane through the associated fin axis approximately equal to the half angle of the tail cone taper. The offset distance D of lugs 44 and the axial distance between the fin shaft axis and the aperture 46 in lug 44 are so chosen that this angle places square aperture 74 of the segmental worm wheel substantially in position to receive the square shank 24 of the fin shaft. As best shown in FIG. 5 taken in conjunction with FIG. 3, a longitudinal slit 88 extends diagonally between the edges of the square shank 75 and an axially extending tapped hole 90 having a divergent conical portion 92 is formed in the end of the fin shaft. After shank 75 is fitted through aperture 74 in the worm wheel, a tapered shouldered screw 94 is tightly driven into opening 90. The engagement of the shoulder of screw 94 against conical portion 92 of the opening expands the split shank within aperture 74, eliminating backlash in this coupling. The end of the shaft 20 of fin 16S projects a short distance beyond the gearbox. The shaft of fin 16P, which does not pass through a gearbox, is the same length as the shaft of fin 16S. These two ends are coupled together for joint rotation by the clamping block attached to yoke assembly 38, which consists of mating members 38a and 38b, FIG. 6. When the mating members are fastened together, they form clamping block portions to engage the square ends of the shafts.

As is conventional with antisubmarine homing torpedoes, torpedo 10 may be delivered to the point of water impact by a rocket propelled missile, or released from an aircraft. The impact of striking the water is lessened by use of drag parachutes. Nevertheless, severe torques are applied to the fin shafts 20 upon water impact, due to the large area of the fins. The fins should remain locked in their neutral position against this torque. In the present apparatus, the requirement of locking the fin in the neutral position is satisfied by a choice of worm parameters which afford resistance to overhauling under the most severe water impact torque conditions. "Overhauling" is defined as the condition where application of a torque to a worm wheel causes the worm to rotate. The parameters which determine overhauling characteristics are the lead angle of the worm and the coefficient of friction between the worm and the worm wheel. The smaller the lead angle the greater the resistance to overhauling. The higher the coefficient of friction the greater the resistance to overhauling. Highly satisfactory results have been obtained in an operational unit like that embodied in the drawing with a lead angle of the worm of 5° and 43", and use of a dry lubricant having a predetermined coefficient of friction of approximately 0.1. Such a dry lubricant may be composited using an epoxy resin base containing a mixture of graphite and molybdenum disulfate.

The unitary actuator assembly 32 is installed in tail cone 12 as follows. With the bolts 60 holding the individual actuators 36 to the ring 34 left loose, the ring 34 is bolted to the fin shaft bosses 22. This is done at a stage of assembly before the motor housing 26, propeller shafts 28a, 28b, and end block 14 are in place. The square aperture 74 of each segmental worm wheel is aligned with the end shank 75 of the corresponding fin, and the fin shank then inserted into the aperture. This is done by the mechanic reaching into the torpedo shell through the hole at the rear end of shell 12, manually shifting the gearbox 48 in a plane perpendicular to the fin axis to position the aperture of the worm wheel into alignment with the fin shaft. The gearbox is shiftable in two dimensions in a plane perpendicular to the fin axis. Elongated slot 58 in gearbox lug 56 allows the gearbox to be shifted in the direction of axis F, providing one dimension of movement. Also, since the aperture 74 is located a substantial distance from bolt 60, rotation of the gearbox about the axis of bolt 60 results in shifting the aperture 74 is an arc about the bolt 60, providing the other dimension of move-

ment. After the inner ends of the fin shafts 20 have been inserted in the worm wheel apertures, the lug bolts 60 are tightened, and the expander screws 94 in the ends of the fin shafts are driven in tight. The inner ends of shafts 20S and 20P are then connected by means of the previously described yoke and assembly 38. The propulsion system components and the propeller shaft block of the tail cone are then affixed in place, and necessary electrical connections made by plugging in to multiterminal connection 42. It will be apparent that installation of the fin and the actuators to the tail cone can be performed without special tools or training, and without the need for any tuning adjustments after the assembly is in place. The feature enabling shifting of the individual actuators into precise alignment with axes B and C, enables interchangeability of shells and actuator assemblies. After assembled to the torpedo shell the apparatus provides rigid mechanical coupling compatible with the high performance of the servomotors, and compactly fits in frustoconical annular space between the propeller shafts and bell-shaped rear end of housing 26 and the inner wall of shell 12.

The servomotor for individual actuator 36S, which drives the shaft of pitch steering fin 16S and fin 16P through the yoke, is operated by conventional pitch steering commands from the torpedo autopilot. In contrast, fins 16U and 16L are independently driven by separate motors. The separate inputs to these motors are derived from a triaxial control arrangement which gives steering fins 16U and 16L combined yaw-and-roll steering commands, the roll-steering commands being a differential deflection of the steering surfaces. An example of a system for deriving a combined yaw-and-roll command steering signals for independently driven upper and lower fins is disclosed in copending application of Edward M. Kimura, Ser. No. 548,820, filed May 4, 1966. Stability of this triaxial control is achieved by providing sufficiently large areas of fins 16, in accordance with conventional hydrodynamic theory. Since the fin shafts 20 are located substantially at the center of pressure of the fins, a minimum of torque is needed to cause their deflection. An important feature of the present mode of operation of triaxial control employing large bodily moveable steering fins is the elimination of any need for any fixed stabilizing surfaces on the tail cone, thereby simplifying the fabrication of the tail cone shell. Another beneficial result is the availability of deflection of the large fin area during initial startup of the torpedo when first dropped in the water. At this time large steering deflections are desired to quickly orient the torpedo along its programmed course from its random orientation after water impact. During homing control phases of the torpedo operation, the steering adjustments are made by a minimum of steering surface deflection because of the large steering control surface provided by the bodily moveable fins. The latter is important because it minimizes the disturbance of the flow to the propellers, and thereby aids in achieving torpedo stability under high speeds.

Obviously many modifications and variations of the present invention are possible in the light of the above teachings. It is therefore to be understood that within the scope of the appended claims the invention may be practiced otherwise than as specifically described.

What is claimed is:

1. A unitary torpedo-steering actuator assembly for positioning within the tail cone of a torpedo employing a mode of control surface deflection for triaxial control of the torpedo in which a first pair of axially aligned control surfaces are jointly deflectable for steering in a longitudinal plane transverse to their axis and a second pair of axially aligned control surfaces are disposed perpendicular to the first pair and in the same transverse plane and are individually deflectable for steering in a longitudinal plane perpendicular to their axis and for torpedo roll control about the tail cone axis, the wall of the tail cone being provided with corresponding first and second diametrically opposite pairs of control surface shaft bearings at a first predetermined longitudinal position, said bearings each being pivotally supporting a control surface with the

inner end of its shaft projecting into the interior of the tail cone, said actuator assembly comprising:

- a. a frame formed as a ring with a substantially rectangular opening and adapted to be affixed to the tail cone disposed transversely across the interior thereof at a second predetermined longitudinal position, the sides of said rectangular opening being perpendicular to the control surface axes, said ring having a first upstanding lug adjoining one of the sides of the pair of sides perpendicular to the axis of the first pair of control surfaces and second and third upstanding lugs adjoining one and the other of the sides of the pair of sides perpendicular to the axis of the second pair of control surfaces, and 10
- b. first, second, and third identical actuators carried by said first, second, and third upstanding lugs for rotating the respective adjacent control surface shaft ends, 15
- c. the shafts of the first pair of control surfaces being rigidly coupled for joint deflection about their axis by a yoke through which the torpedo propeller shafting may extend, 20
- d. each actuator comprising a housing having a worm driven by a reversible motor and meshing with a worm wheel, said worm wheel having an aperture for receiving the inner end of the adjacent control surface shaft, 25
- e. each actuator having an associated means permitting shifting of said actuator housing in a plane perpendicular to the control surface shaft axis and for securing it in a desired position, said associated means comprising a lug on the actuator housing having an elongated aperture and a screw extending through said aperture and engaging the associated lug on the frame, 30
- f. whereby said actuator assembly may be positioned in the tail cone as a unitary organization by affixing the ring to the tail cone at said second predetermined position and adjusting the position of each actuator housing to receive the inner end of the control surface shaft. 35

2. Apparatus in accordance with claim 1 further for use with a torpedo adapted for aircraft dropped launching into the

water with the control surfaces in their neutral position and of construction having a tail cone having a smooth exterior surface without fixed external stabilizing fin appendages and

- g. the individual control surfaces each comprising a bodily deflectable steering fin having sufficient fin area to enable control of the stability of the torpedo by said mode of torpedo control under the conditions of absence of fixed external stabilizing fin appendages,
- h. said worm being of the nonoverhauling type, whereby said actuator assembly construction inherently locks said fins in their neutral position against water entry forces acting upon the steering fin area.
- 3. An assembly in accordance with claim 1, wherein:
- i. said second predetermined longitudinal position being forward of the first predetermined longitudinal position and the upstanding lugs projecting forwardly from the front face of the ring, the meshed worm and worm wheel of each actuator being disposed rearward of the ring with the lug on the actuator housing extending through the opening in the ring to a position at least partially in juxtaposed relation to the adjacent upstanding lug on the ring,
- j. each upstanding lug being offset by a predetermined distance to a predetermined side of longitudinal plane of the associated steering fin shaft,
- k. the axis of the worm of each actuator being inclined to said longitudinal plane by a predetermined angle approximately equal to the half-included angle of the tail cone, and
- l. said worm drive motor of each actuator being disposed forward of the ring and connected to the worm through shaft extension extending through the opening in the ring whereby the assembly structure is disposed in a conical annular envelope dimension adjacent to the inner wall of the tail cone to provide a frustoconical void space forward of the ring into which propulsion drive components of the torpedo may project.
